GEORGE E. HOWARD, OF BUTLER, PENNSYLVANIA, ASSIGNOR TO HARTFORD-EMPIRE COMPANY, OF HARTFORD, CONNECTICUT, A CORPORATION OF DELAWARE.

METHOD OF AND APPARATUS FOR FORMING PLATE GLASS.

Application filed December 27, 1923. Serial No. 157,027.

My invention relates to the manufacture of sheet glass by the intermittent rolling of plates from masses of molten glass, and the transfer of the plates to a lehr for annealing. In the rolling of plate glass, it has been customary to allow the glass sheet to remain upon the casting table until it has become set or hardened sufficiently to permit it to be moved into a lehr without distorting the glass through stretching or wrinkling. That end of the plate which is first rolled is, of course, cooling during the time required for the roller to pass to the other end of the table, so that the first named end is much colder than the opposite end of the plate, with the result that if the glass plate is quickly shoved into a lehr, as is customary, there is an uneven condition present, arising from non-uniform tension as between various portions of the sheet and non-uniformity in temperature as between such portions.

In attempting to overcome a non-uniform condition in the various portions of the sheet when it enters a lehr, the sheet has been permitted to lie on the table until that end which is formed last, more nearly approximates in temperature the initially formed end thereof, reliance being placed upon the fact that the sheet cools more rapidly immediately after it has been rolled than at later stages, so that the hotter end of the plate will, for a period of time, cool more rapidly than will the initially formed end after it has become partially chilled. However, such procedure is a mere make-shift and only tends toward an approximation of the desired result, it being impossible, from a practical standpoint, to permit a sheet to remain upon the table until it has cooled to ordinary atmospheric temperature.

My invention has for its object the provision of a method and a means whereby intermittently rolled sheets may be introduced into the lehr in such manner that all parts of each plate, as it enters the lehr, will be in substantially the same condition as to temperature and as to tension between the particles.

Some of the means by which my invention may be practiced are shown in the accompanying drawing, wherein Figure 1 is a plan view of a casting table and a portion of a lehr embodying my invention; Fig. 2 is a longitudinal sectional view thereof; Fig. 3 is a plan view of a modified arrangement where-

by my invention may be practiced; Fig. 4 is a longitudinal sectional view of the apparatus of Fig. 3, and Fig. 5 is a view taken on the line V—V of Fig. 3, but showing the feed rolls in operative position relative to the glass.

Referring to Figs. 1 and 2, I show a casting table 6 which may be of somewhat the usual form, but which is pivoted, at its forward end, on a supporting structure 7. The rear end of the table is normally supported by a bracket 8, but has connection with a plunger 9 that is connected to a piston which operates in a cylinder 10 to raise the table to the position indicated by the dotted lines in Fig. 2, as hereinafter explained.

Forwardly of the table, I provide a lehr 11 which may be of the usual form. At the entrance to the lehr, I provide an apron 12 which is hollow, and is provided with openings 13 in its sides through which a heating or cooling medium may be introduced to control the temperature of the glass previous to its entry into the lehr. Above the apron 12, I provide a casing 14 that has openings 15 through which a heating or cooling medium may be introduced, as in the case of the apron 12. A conveyor belt 16 is driven in any suitable manner and serves to advance the plates of glass into and through the lehr 11.

When a mass of glass has been deposited upon the table 6, as indicated at 17, the table being in horizontal position, a sheet-forming roll 18 is advanced across the table to spread the glass and form a sheet 19. The roll 18 moves rearwardly of the table and may be rolled upon the bracket 8, so as to be clear of the table. With the roller 18 out of the way, and sufficient time having elapsed to permit the sheet 19 to set, fluid pressure is admitted to the lower end of the cylinder 10 to elevate the rear end of the table 6 to the position indicated by dotted lines. Thereupon, the edges of the sheet are grasped by tongs 20, or in any other suitable manner, to move the sheet 19 forwardly into engagement with the belt 16. The tilting of the table serves chiefly to permit the sheet to be more easily advanced and also to permit it to be advanced while all portions thereof are still plastic. It is customary to cover the table with dry sand to facilitate sliding of the sheet into the lehr, and I may prefer to allow the table to remain horizontal during such transfer.

In advancing the sheet to the lehr belt, I

move it at such speed that the rear portion of the sheet will be permitted to remain in contact with the table and exposed to the atmosphere for a period of time substantially equal or approximating that at which the front portions or first formed parts are so exposed, so that all portions of the sheet will enter the lehr at approximately a given temperature. While a more uniform condition will be secured by advancing the sheet continuously at the same rate of speed at which it was rolled, I may find it convenient to advance the sheet by stages. For instance, one stage of movement may bring the forward end of the sheet to the point *a*, and another stage of movement may bring such end to the point *b*, there being as many intermediate stages as desirable or convenient. However, it is highly important that the rate of speed at which the plate is advanced into the lehr is proportionate to the rate at which it was rolled.

Referring now to Figs. 3 to 5, I show a sheet-forming roll 18^a, a table 6^a, a lehr 11^a, and a conveyer belt 16^a. These parts may be all of substantially the form of the corresponding parts of Figs. 1 and 2, except that the table 6^a is shown as rigidly mounted.

Plates of glass are formed upon the table 6^a as on the table 6, but instead of advancing the plates by tongs, I provide a pair of feed rollers 22 at each edge of the table. These feed rollers are mounted in bearings 23 and 24 that are in turn pivotally supported upon slides 25. The slides are connected to piston rods 26 that are actuated by fluid-pressure cylinders 27 to move the slides and the feed rollers carried thereby toward and away from the edges of the sheet 19^a.

The edges of the table have cut out portions 28 (Fig. 5) into which table segments or blocks 29 may be moved so that their top surfaces are flush with the top surface of the table. The blocks 29 are mounted upon pistons that operate within cylinders 30, so that the blocks may be raised to and lowered from operative position, as desired.

With the blocks in their uppermost positions and the rollers 22 retracted, as shown in Fig. 3, a pot of glass may be poured upon the table and rolled to sheet form. When the glass has become sufficiently set, the fluid pressure is exhausted from the cylinders 30, to permit the blocks 29 to move down. Fluid pressure is then admitted to the cylinders 27 to advance the slides 25, carrying the rollers 22 toward the position shown in Fig. 5. At the beginning of this movement, the inner ends of the rollers 22 are held in expanded position by tension springs 31, that exert a tilting force upon the rollers. As the rollers move inwardly, cam shoulders 32 that are formed on their bearings 23 engage the edges of bracket members 33, to move the rollers of

each pair toward each other, against the tension of the spring 31, and into engagement with the edges of the plate 19^a. The rollers are driven from telescopic shafts 34, that are provided with universal joints 35, and with long-toothed gear wheels 36 that are mounted on the shafts of the rollers.

The rollers 22 will have a peripheral speed approximating and proportionate to the rate at which the sheet was rolled by the roller 18^a. The conveyer belt 16^a may either be driven intermittently, so that it will advance a transferred plate of glass only during operation of the feed rollers 22, or it may be operated at a continuous slow speed.

It will be seen that when the forward end of the sheet first encounters the lehr belt 16^a, the friction between the belt and the plate will be insufficient to exert a substantial advancing force on the glass plate, because a greater portion of the weight of the plate is resting upon the table, with consequent greater friction between the plate and the table than is present between the plate and the lehr belt. When substantially half of the plate has entered upon the lehr belt, I may separate the rolls 22 from driving engagement with the sheet, by admitting fluid pressure to the inner ends of the cylinders 27, thus withdrawing the member 25 and permitting the springs 31 to expand the rolls 22.

Viewing the foregoing as a two stage method—(a) the stage of rolling, and (b) the stage of transferring; during the first stage, the first formed end of the sheet is exposed to cooling contact with the table and with the atmosphere for a longer period of time than is the last formed end thereof. During the operation of transfer to the lehr, that end of the sheet which was exposed for a longer period is exposed for a proportionately shorter period and the last formed end is exposed for a proportionately longer period, thus, so far as cooling environment as between the different portions of the sheet is concerned, the conditions during transfer are the reverse of those present during the stage of rolling.

By my method, I am enabled to introduce a plate into the lehr, without the necessity of passing it through a series of temperature-controlling devices. In such prior art devices, this has been considered necessary owing to the widely varying differences in temperature as between various portions of the plate at the time it is removed from the table. By my method, I automatically secure the effect of equalization of temperature, which eliminates the expense of additional equipment and labor.

I claim as my invention:

1. The method which comprises rolling a plate of glass upon a table while the latter is stationary, and advancing the plate into

a lehr, with its first formed portion foremost, at a rate of speed dependent upon the rate at which the sheet was rolled.

2. The method which comprises rolling a plate of glass upon a table while the latter is stationary, and advancing the plate into a lehr with its first formed portion foremost, at a rate of speed proportional to the rate at which the sheet was rolled.
- 10 3. Sheet glass handling apparatus comprising a table having a segmental portion that is movable to permit of engagement by sheet advancing members with that part of the glass which was supported by said segmental portion.
- 15 4. Sheet glass handling apparatus comprising a table having a removable segmental portion at one edge thereof, members for advancing the sheet, and means for moving said members into engagement with the glass when said segmental portion is removed.
- 20 5. Sheet glass handling apparatus, comprising a table having a removable segmental portion at one edge thereof, members for advancing the sheet, and means for moving said members into gripping engagement with the glass when said segmental portion is removed.
- 25 6. Glass handling apparatus, comprising a pair of feed rolls for engaging an edge of a sheet of glass, means for moving said rolls in a direction parallel to the plane of the glass,
- 30
- and means for simultaneously moving said rolls relative to one another in a direction transversely of said plane.
7. Sheet glass handling apparatus, comprising a pair of feed rolls, a bearing for each of said rolls, means for driving said rolls, means for shifting the position of said bearings as a unit, and means for simultaneously moving said bearings relative to one another to vary the distance between the rolls.
8. Sheet glass handling apparatus comprising a support for the glass, a device for advancing the glass, and means for moving said device into and out of driving engagement with the glass, in directions parallel to and transversely of the plane of the sheet of glass.
9. Sheet glass handling apparatus comprising a support for the glass, a pair of feed rollers mounted for oscillation in a plane transverse to the plane of the glass, means for yieldably holding said rollers in expanded position, means for shifting said rollers in a direction parallel to the plane of the sheet, and means for moving said rollers in opposition to said yieldable means, in order to effect driving engagement thereof with the glass.

Signed at Butler, Pa., this 11th day of December, 1926.

GEORGE E. HOWARD.
